UNITED STATES PATENT OFFICE.

LESTER W. SEEMAN AND JAMES C. MORSE, OF FORT STEILACOOM, WASHINGTON.

VACUUM-WALLED REFRIGERATOR.

1,091,968.

Specification of Letters Patent. Patented Mar. 31, 1914.

Application filed May 14, 1913. Serial No. 767,637.

To all whom it may concern:

Be it known that we, LESTER W. SEEMAN and JAMES C. MORSE, citizens of the United States, residing at Fort Steilacoom, in the county of Pierce and State of Washington, have invented new and useful Improvements in Vacuum-Walled Refrigerators, of which the following is a specification.

The invention relates generally to improvements in refrigerators and particularly to a refrigerator in which the heat insulating properties are obtained through the use of a vacuum.

The invention is particularly directed to the means for securing the usual porcelain receptacle in the refrigerator in the manner to maintain an effective vacuum space between said receptacle and the body of the refrigerator.

20 The invention in the preferred form of details will be illustrated in the following specification, reference being had particularly to the accompanying drawings, in which:—

25 Figure 1 is a vertical section through the improved refrigerator. Fig. 2 is a similar view taken at right angles to Fig. 1. Fig. 3 is a horizontal section. Fig. 4 is an enlarged broken sectional view illustrating the means 30 for securing the terminal edges of the porcelain receptacle in place at the door opening. Fig. 5 is a plan of the separator. Fig. 6 is a side elevation of the separator used for supporting the porcelain lining 35 from the body.

Referring particularly to the accompanying drawings the improved refrigerator comprises the usual exterior casing 1 of wood, the parts of which may be connected 40 and assembled in any desired manner. A door opening 2, one or more as the case may require, is formed in the exterior casing at an appropriate point or points. The casing about the door opening is materially thickened as at 3, preferably corresponding to the aggregate thickness of the wall of the refrigerator when completed. The surface of the walls of the door opening are preferably of the usual stepped or other irregular 45 formation as at 4. The door 5, which is hinged and otherwise secured to the casing in any desired manner has an edge formation corresponding to the surface of the walls of the door opening, and beyond said

edge formation is materially reduced in thickness to provide a space 6.

Secured to the interior of the casing throughout the surface thereof, and to the interior of the space 6 of the door or doors is a lining 7 preferably of sheet metal. 60 This lining covers the interior surface of the refrigerator casing and doors except on the inner surface of the relatively thickened portions of the casing adjacent the door opening and of the corresponding portion 65 of the door. The lining extends throughout the length and breadth of that length of the thickened portion at right angles to the wall of the refrigerator, as at 8, and in line with the inner surface of the enlargements of the casing and door is bent laterally to provide a flange 9 which overlies the 70 casing wall and the reduced wall of the door or doors.

A porcelain receptacle 10, made in sections and secured together at the meeting edges of such sections in any desired or preferred manner is secured in place in spaced relation to the metal lining 7, said porcelain receptacle, which it will be understood forms the interior surface of the refrigerator, is held in spaced relation to the metal lining by what we term separators comprising duplicate heads 11 including a series of radiating members 12, the heads 25 being connected by a pin 13 joining their centers. The heads are of light metal and the aggregate width of the separator corresponds to the similar dimension of the vacuum chamber, that is, the distance between the proximate surfaces of the porcelain receptacle and metal lining. The end edges of the particular sections of the porcelain receptacle terminating adjacent the enlargements of the casing and door are seated beneath the flanges 9, as at 14, and are appropriately sealed to said flanges. 90

Any desired means may be employed for exhausting the air from the space between the porcelain receptacle and metal lining so 100 as to provide in effect a heat insulating space throughout practically the full interior surface of the casing and doors.

In utilizing the porcelain receptacle as one wall of the vacuum chamber, we avoid 105 the necessity of the usual sanitary lining which would otherwise be additionally required in the refrigerator, and by the use

of the separators described, we provide a substantial pressure resisting interior wall for the vacuum chamber, as will be obvious.

What is claimed as new is:—

- 5 A refrigerator having an outer casing provided with a door opening and an interior wall corresponding in size and shape to the dimensions of the outer casing, said interior wall comprising a metal lining for
- 10 the outer casing and a porcelain receptacle held in spaced relation to the metal lining, said lining being formed adjacent the door opening with laterally projected flanges,

the terminal edges of the porcelain receptacle being sealed beneath said flanges 15 whereby the air may be exhausted from the space between the metal lining and the porcelain receptacle.

In testimony whereof we affix our signatures in presence of two witnesses.

LESTER W. SEEMAN.
JAMES C. MORSE.
